UNITED STATES PATENT OFFICE

ROBERT P. SMILIE, OF OAKLAND, CALIFORNIA

PORTABLE HOPPER

Application filed June 24, 1929. Serial No. 373,327.

The invention relates to portable hoppers.

One of the objects of the invention is to provide a portable hopper having a body comprising a hopper from which the supporting truck may be readily withdrawn.

A further object of the invention is to provide a portable hopper having means for supporting the hopper when the truck is withdrawn therefrom and means for readily raising and lowering one end of the hopper for discharging the contents thereof from the opposite end.

For a more comprehensive and clearer understanding of the invention reference may now be had to the following specification taken together with the accompanying drawings in which the preferred embodiment of the invention is shown and in which:

Figure 1 is a plan view of the underside 20 of the device.

Figure 2 is a longitudinal vertical section taken on line 2—2 of Figure 1.

Figure 3 is a side elevation of the portable hopper with the supporting truck detached 25 showing the means for supporting one end of the hopper and mechanism for raising and lowering the other end, the hopper being indicated in the raised position by dotted lines.

Figure 4 is a side elevation of the hopper showing the pivoted support for the discharge end thereof when the supporting truck is withdrawn from thereunder.

Figure 5 is a transverse vertical sectional 35 view taken on line 5—5 of Figure 4.

Figure 6 is a front end view of the hopper shown in raised position after the removal of the supporting truck from thereunder.

Like reference characters indicate like 40 parts throughout the several figures thereof. The portable hopper comprises a body 10 which is preferably constructed of sheet metal suitably secured to an angle iron frame work 11. The body 10 being open at the 45 top having side walls 12 and 13 which taper or converge from the front end 14 to the rear end 16. The bottom of the hopper from its approximate center inclines upwardly to the rear end as indicated at 18. Wheels 19 50 are suitably mounted on the truck frame 21.

The frame 21 is substantially rectangular in shape, the side members thereof extending beyond the rear transverse members as at 22. U-shaped brackets 23 secured to the bottom 17 of the body portion 10 receive the extensions 22 of the truck frame 21 in sliding engagement therein.

Secured to the forward transverse member of truck frame 21 is draw bar 24 which extends outwardly from the frame and beyond the front wall 14 of the body portion 10 in order that it may be secured to a motor vehicle for towing the portable hopper. An angle iron 27 is secured to the front wall 14 of the body portion by its vertical flange and has an aperture through the horizontal flange thereof for the reception therein of a bolt 28 passed therethrough and into an opening in the draw bar which registers with the aperture in the angle iron for securing the body portion 10 to the draw bar 24 thereby preventing the withdrawal of extensions 22 of the truck frame 21 from the U-shaped member 23. In the rear end wall 16 of the body portion 10 is a gate extending transversely across the entire end of the body portion 10 and slidably engages tracks 27 secured to the opposite sides 12 and 13 of the body portion 10. A lever 28 pivoted at the approximate center of transverse brace 28a as 80 at 40 is also pivotally secured to the gate as at 41, for raising and lowering the gate in order to discharge the contents of the body in such proportions as may be desired. Support 29 having divergent legs 42 and 43 85 and transverse braces 44 and 45, is pivotally related to sleeper 46 at the rear end of the body portion 10 for fulcruming the body portion thereon in order to discharge the contents of the body by raising the forward end 90 thereof.

It will be noted (see Fig. 4) that the base of support 29 is elevated above the roadway during the course of travel of the portable hopper.

A tilting mechanism comprising spaced apart standards 31 having sheaves 32 rotatably mounted at their upper ends for the passage thereover of cables 33, is provided for raising and lowering the receiving end 100.

- of the hopper which is pivoted at its discharge end on support 29 for the purpose of discharging the contents of the hopper by gravity through gate 26 when the front end 5 of the hopper is raised above the top of support 29. Standards 31 of the aforesaid tilting mechanism are provided with braces 49 pivotally related to the standards at their upper ends and adjacent the upper ends of 10 the standards and are for the purposes of preventing the tilting of the standards when power is applied to cables 33 by the tow motor, for instance, for raising the receiving end of the hopper. Cables 33 may be affixed to 15 the receiving end of the hopper in any suitable manner as at 34. If desired, a winch of the usual construction may be provided for the raising and lowering of the receiving end of the hopper.
- 20 It will be noted (see Fig. 2) that the axle of the truck is positioned forwardly of the center of the body portion 10 which will result in the gravitation downwardly of the discharge end of the body portion until it 25 comes to rest upon the support 29, at which time power may be applied to cables 33 and the receiving end of the body supported thereby, and the pin 26 be withdrawn from engagement with the angle iron and the draw 30 bar and the towing motor moved away from and out of engagement with the hopper at which time the receiving end of the hopper may be lowered to the ground by slackening the cables as clearly shown in Figure 3.
- 35 When in this position the charge of a delivery truck may be dumped into the hopper and the receiving end of the hopper raised as heretofore described and shown in the dotted lines of Figure 3, and the charge caused 40 to flow through the gate at the discharge end thereof and discharged in suitable quantities, such as for instance to sufficiently fill a wheelbarrow, to be conveyed to a point on the job where its use is required.
- 45 Supporting legs 36 are pivotally related to the exterior faces of walls 12 and 13 as at 48 for supporting the front end of the hopper when the power is withdrawn from cables 33. Keepers 37 affixed to the bottom 50 of the hopper are provided for securing these legs against downward movement when it is desired that the receiving end of the hopper be lowered to the ground.
- I claim:
- 55 A portable hopper comprising a body portion adapted to be supported by a truck frame, tongues and U engaging means for said body portion and said truck frame, means for detachably securing the body portion 60 to the truck frame against movement relative thereto, the bottom of the rear of said body portion being inclined upwardly for a portion of its length, a depending support pivotally related to the rear end of the 65 body portion, a gate in the rear end thereof

and pivoted lever means for raising and lowering the gate.

In testimony whereof I have affixed my signature.
